KNITTING MACHINERY

Henry Peters, Clifton, N. J., assignor to Universal Patents Holding Co., Weehawken, N. J., a corporation of New Jersey

Application April 23, 1931, Serial No. 532,169

4 Claims. (Cl. 66—96)

The invention relates to improvements in flat knitting machinery and more particularly to means for making lace designs with a picot bar on all parts of the stocking blank, from one side 5 to the other, in the welt, after the welt or on any part of the blank; in addition means are embodied in the same machine for making net mesh designs with net mesh bars, the same being made from one side to the other of the blank or on any 10 part of the blank. The feature of the invention is that both the aforesaid lace designs and net mesh designs may be made on the blank for a full fashioned hose during the knitting of the 15 hose and without removing the hose from the machine.

In accordance with present practice, great care must be exercised and a large amount of time 20 must be consumed in setting up a knitting machine for the formation of lace designs. The same holds true for setting up the machine for net mesh designs. It is often desirable in the manufacture of fancy hose to have a lace design on parts of the hose and to have a net mesh design on other parts. The only possible way to 25 do this with the present machines is to transfer the partially completed blank from one machine to another. As this operation might have to be performed a number of times during the manufacture of a single blank it would make the cost 30 of the completed stocking prohibitive.

The principal object of the present invention is to provide a simple method whereby either lace 35 designs or net mesh designs may be formed on any desired part of the stocking without removing the blank from the machine. In this way, a very fancy and attractive stocking may be made in an efficient and economical manner.

The invention will be further described in the following specification and illustrated in the 40 drawing accompanying same and forming a part thereof.

Referring to said drawing:

Figure 1 is a fragmentary front elevation;

Figure 2 is an end view, the shafts being in section; and

Figure 3 is a fragmentary view of a stocking blank in which parts of the design are more or less diagrammatically illustrated.

It is to be understood the invention is applicable to any standard type of flat knitting machine, either a legger or a footer, or a unit machine in which the complete blank is knit.

The reference numeral 5 designates the lace bar which is carried by suitable arms 6 secured 55 to the shaft 7. The shaft 7 is movable longitudi-

nally by any conventional form of lace-work operating mechanism. It is also mounted in the usual manner so that it may be oscillated.

The lace bar carries lace points of picot points 8. The points 8 operate in the usual manner; 60 that is, in forming a design they transfer stitches from some of the main frame needles 9 to adjacent needles to give the lace effect. The form of design to be made determines the positioning of the points. It is understood the frame needles 65 9 are of the known spring beard type mounted in the needle bar 10 in a conventional manner.

Shafts 11 and 12 through the medium of arms 13—13 and 14—14 carry net mesh bars 15 and 16. The net mesh bar 15 carries lace or picot 70 points 17 and is of sufficient width so as to extend substantially from selvage to selvage of the stocking web or blank. The points 17 will be arranged on the net mesh bar in accordance with the net mesh design being made.

The net mesh bar 16 carries points 18 and the bar is considerably shorter than the bar 15. The net mesh bar 16 is used between the high heel and heel reinforcement and on the instep portion in 75 the foot of the blank.

The shafts 11 and 12 are movable longitudinally by the lace work operating mechanism and may be oscillated in the usual manner to engage the frame needles 9.

In Figure 3 the reference numeral 20 designates the upper part of the stocking blank or web, the welt being indicated at 21. The lace design 22 or any other design which extends across the blank is made with the lace points 8 after the welt, or in the welt or on any other 90 part of the stocking. The net mesh design is indicated at 23 and this design or any other form of the net mesh design may be formed on any part of the stocking by the means heretofore described.

It is to be understood that the lace bar 5 and the net mesh bars 15 and 16 are all caused to function by the lace work operating mechanism. Inasmuch as mechanisms for moving a point bar are well known in the art for producing both narrowing and lace work effects, a description of this mechanism is believed unnecessary, and is therefore omitted.

Such changes as would occur to one skilled in the art are to be considered as coming within 105 the scope of the appended claims.

I claim:

1. A flat full-fashioned knitting machine having in combination with a series of needles and their cooperating knitting elements, a transfer 110

point bar having points spaced at intervals lengthwise of the needle series, a second transfer point bar having points spaced at intervals lengthwise of a portion of the needle series covered by said first-mentioned bar, parallel lengthwise movable shafts having a fixed spaced relationship to each other on each of which one of said transfer point bars is mounted to swing into and out of operative position, said bars and shafts being arranged to permit the movement of said bars alternatively into operative position when the other of said bars occupies a raised inoperative position.

2. A flat full-fashioned knitting machine having in combination with a series of needles and their cooperating knitting elements, a lace point bar having points spaced at intervals substantially the full width of the fabric, a longitudinally movable shaft on which said bar is pivotally supported to move into and out of operative position, a net mesh bar having points spaced at intervals the width of a portion of the fabric, and a separate lengthwise movable shaft located in fixed spaced relationship to said first bar and on which said net mesh bar is supported to swing into and out of operative position, said shafts and bars being arranged to permit the unobstructed movement of either of said bars about its supporting shaft into operating position when the other of said bars occupies a raised inoperative position.

3. A flat full-fashioned knitting machine having in combination with a series of needles and their cooperating knitting elements, a transfer point bar having points spaced at frequent intervals lengthwise of the needle series, a longitudinally movable shaft on which said bar is supported to swing into and out of operative po-

sition, a second lengthwise movable shaft located in fixed spaced relationship to and above said first-mentioned shaft, and a second transfer point bar having points spaced at frequent intervals over substantially the same portion of the needle series, and supporting arms for said latter bar mounted on said second-mentioned shaft to permit the unobstructed movement of said second bar about said shaft into operative position with said first-mentioned bar in its raised inoperative position.

4. A flat full-fashioned knitting machine having in combination with a series of needles and their cooperating knitting elements, three parallel endwise movable shafts mounted in fixed spaced relationship to each other at varying distances from the needle series, a transfer point bar having points spaced at intervals the width of a portion of the needle series and mounted on the shaft nearest said needle series to swing into and out of operative position, a second transfer point bar having points spaced at intervals lengthwise of the needle series and including the portion covered by said first-mentioned bar and provided with supporting arms secured to the intermediate shaft to permit an unobstructed swinging movement of the bar into operative position for a raised inoperative position of said first-mentioned bar, and a third transfer point bar having points spaced at intervals substantially the full width of the needle series and provided with supporting arms mounted on said third furthest removed shaft arranged to permit an unobstructed swinging movement of said bar into operative position for a raised inoperative position of both said first and second bars.

HENRY PETERS.
